US00D816518S

(12) **United States Design Patent** (10) **Patent No.:** **US D816,518 S**
(45) **Date of Patent:** **** May 1, 2018**

(54) **MULTI-SENSOR**

- (71) Applicant: **View, Inc.**, Milpitas, CA (US)
(72) Inventors: **Stephen C. Brown**, San Mateo, CA (US); **Alexander Rumer**, Milpitas, CA (US); **Nilesh T. Desai**, San Jose, CA (US)
(73) Assignee: **View, Inc.**, Milpitas, CA (US)
(***) Term: **15 Years**
(21) Appl. No.: **29/560,076**
(22) Filed: **Apr. 1, 2016**

Related U.S. Application Data

- (63) Continuation of application No. 14/998,019, filed on Oct. 6, 2015.

CLAIM

We claim the ornamental design for a multi-sensor, as shown and described.

DESCRIPTION

FIG. 1 is an isometric view of a multi-sensor.

FIG. 2 is a front view of the multi-sensor.

FIG. 3 is a back view of the multi-sensor.

FIG. 4 is a right side view of the multi-sensor.

FIG. 5 is a left side view of the multi-sensor.

FIG. 6 is a top view of the multi-sensor.

FIG. 7 is a bottom view of the multi-sensor; and,

FIG. 8 is an off-angle view of the multi-sensor.

Diagonal line shading is used to indicate a transparent area of the multi-sensor through which light may pass.

Stipple shading is used in FIGS. 1 through 8 to convey surface contours; the stipple shading is not to be understood as conveying a particular surface finish.

The broken lines show portions of the multi-sensor that form no part of the claimed design.

The “dash-dot” broken lines define the bounds of the claimed design and form no part thereof.

1 Claim, 8 Drawing Sheets
